UNITED STATES PATENT OFFICE.

GEORGE G. FIRTH, OF BROOKLYN, NEW YORK.

SHIELD FOR STAND OR RANGE BOILERS.

1,174,060.

Specification of Letters Patent. Patented Mar. 7, 1916.

Application filed June 7, 1913. Serial No. 772,268.

To all whom it may concern:

Be it known that I, GEORGE G. FIRTH, a citizen of the United States, residing at Brooklyn, in the county of Kings and State 5 of New York, have invented certain new and useful Improvements in Shields for Stand or Range Boilers, of which the following is a specification.

This invention relates to an improvement 10 in what is known as stand or range boilers, the object of the invention being to provide improved means for ornamenting the same whereby the ordinary stand or range boiler may have a clean and sanitary appearance 15 and may correspond with other fixtures of a kitchen.

As is well known it is now usual to have the fixtures of a kitchen of white enamel or porcelain, the walls of the kitchen likewise 20 being not infrequently tiled, but so far as I am aware there has been no practical way of having the stand or range boiler correspond with the tiled walls and other white fixtures of a kitchen. It is extremely difficult, if not entirely impractical to enamel 25 the boiler itself for among other reasons the heat of the boiler is likely to crack the enamel when such enamel is applied directly on the boiler.

Therefore, the present improvement consists in providing a simple and comparatively inexpensive and efficient means which may be readily applied to and detached from an ordinary stand or range boiler to give 35 thereto the same appearance as other fixtures contained in the kitchen and which improvement may be applied to range or stand boilers already in use.

In the drawings accompanying and forming part of this specification, Figure 1 is a side elevation of the usual vertical stand boiler having in section this improvement applied thereto; Fig. 2 illustrates the same as applied to a horizontally supported range 45 boiler.

Similar characters of reference indicate corresponding parts throughout the different figures of the drawings.

The stand or range boiler 2 shown of the 50 vertical type in Fig. 1 is usually supported by a stand 3 resting upon the floor and is provided with the usual inlet and outlet pipes. For the purpose of giving the same an ornamental appearance, I provide a shell 55 4 having in the form shown in Fig. 1 a lower

open end as at 5, which shell is provided at its upper end with a circular opening 6 to permit the passage of the usual pipes to the stand boiler. This shell is preferably provided with a reinforced edge 7 which may 60 if desired be located on the outside of the top portion 8 of the shell, but in the present instance is shown located on the underside thereof so as to rest on the top of the stand boiler 2 and thus form an efficient means of 65 supporting the same with the annular top 8 a slight distance away from the top 9 of the stand boiler. The shell 4 is so made that it is slightly larger than the stand boiler 2 itself, and will thus constitute a means for 70 maintaining the heat within the stand boiler while at the same time the air space between the two will be such that the heat of the boiler will not crack the enamel. This shell 4 is 75 enameled in any of the usual ways to give it the desired ornamental appearance, as for instance it is dipped in white enamel and baked in the usual way of applying enamel, the shell of course being made of a suitable metal to take the enamel.

It will thus be observed that in the form shown in Fig. 1 both the bottom and top are open, the bottom being entirely open while the top is provided with a circular opening formed by the annular portion 8 adapted to fit over a portion of the top 9 of the stand boiler. To attach the ornamental shell it is merely necessary to uncouple the usual supply pipes and place the shell in position, it of course being provided with an opening 10 at its side for the passage of the outlet pipe. When it is desired to apply this improvement to horizontal boilers the shell preferably consists of a body 12 and a pair of end members 13 and 14, the several parts being provided with the necessary openings for the passage of the pipes. Each end member may be in the form of a flanged cover adapted to fit over the body member 12. Of course, it will 85 be understood that the body member 12 and one of the covers 14 might be used in place of the structure shown in Fig. 1, as no end member will be necessary at the lower 90 end of the shell shown in Fig. 1, for the reason that this is usually near the floor. When that form of the improvement 105 shown in Fig. 2 is used it will be left to the plumber or mechanic installing the structure to properly space the enamel shell from 110

the boiler, which he can readily do by simply placing a small piece of asbestos block between the upper side of the boiler and the shell at the ends.

5 By means of this improvement I am able to apply an enameled shell quickly and readily to an ordinary stand or range boiler which shell can be readily detached should it be necessary to renew the stand boiler 10 on account of leakage or otherwise, and which shell can be readily washed and will give to the boiler the same general appearance that other enamel, porcelain, or tiled articles may have in a kitchen, and this at a 15 comparatively moderate expense.

The bead shown in Fig. 1 resting upon the boiler does not prevent the circulation of air, for the reason that there is no air-tight joint at this point, and there could not well be, 20 for, as is well known, there are many imperfections in the metal of a boiler of this kind, it not being perfectly true, and neither is the bead perfectly true; consequently, there

is nothing to prevent the passage of air between the bead and the top of the boiler. 25

I claim as my invention:

1. A stand or range boiler provided with a detachable open-ended enameled shell of larger size than said boiler, said shell having an inturned bead around one of its open 30 ends and adapted to rest on said boiler thereby to maintain the boiler and shell spaced apart.

2. As an article of manufacture, a detachable enameled shell for stand or range boilers, said shell being open to the atmosphere adjacent to the boiler at both ends thereof, the opening at the upper end being surrounded by an inwardly turned reinforcing bead effective to maintain the boiler and 40 shell properly spaced apart.

GEORGE G. FIRTH.
